UNITED STATES PATENT OFFICE

SYLVESTER HOWELL, OF FAIRBANKS, ALASKA

METHOD AND APPARATUS FOR UNDERGROUND HYDRAULIC MINING

Application filed July 16, 1929. Serial No. 378,601

This invention relates to underground hydraulic mining, particularly to placer mining, and aims primarily to provide an improved method and apparatus for mining 5 gold and other rare metals at depths too great for dredging or open cutting, which is much more efficient and economical in time and labor than the drifting or other methods heretofore employed for such purposes.

10 Contemplated by the present invention is the provision of an underground hydraulic mining method and apparatus embodying certain novel features, principally among which are: Mining conditions are made to order; all apparatus employed is located underground; relatively few operators are necessary; mining operations are initiated at points furthest away from the mine shaft and are advanced towards the same; simultaneous thawing and cutting away the material containing the rare metals is effected; the cutting water is utilized subsequent to cutting operations for conveying the mined material from the working face to the mine shaft and concurrently therewith for extracting the rare metals therefrom; the water is separated from the waste material or tailings and stored in a sump from which it is returned under pressure and in a heated condition to the working face, thus permitting of repeated or continuous use of such water for sluicing purposes; loss of water through absorption and in the waste material or tailings is slight; disposal of the waste material or tailings is effected by hoisting or elevating the same to the surface, all of which are important features of the invention and are to be correlated in the broad aim of enhancing the efficiency of the method and apparatus.

The above, and additional features which will hereinafter be more specifically treated, are attained in the manner set forth in the following specification and then more clearly pointed out in the claims, which are appended hereto and form part of this application.

With reference to the drawings, in which are illustrated several embodiments of the invention, and throughout the several views

of which like characters of reference designate similar parts:

Figure 1 is a vertical longitudinal section of a mine comprehended by the present invention.

Fig. 2 is a plan view of the same, certain parts being shown in horizontal section for clarity of illustration.

Fig. 3 is a vertical transverse section taken through line 3-3 of Fig. 1.

Fig. 4 is an enlarged fragmentary vertical longitudinal section of the central portion of the mine.

Fig. 5 is an enlarged fragmentary horizontal section taken through line 5-5 of Fig. 4.

Fig. 6 is an enlarged longitudinal section of one of the mine tunnels, illustrating the manner of sluicing the pay dirt when the working face approaches the mine shaft.

Fig. 7 is a slightly modified form of means 70 for hoisting the gravel from the mine.

Fig. 8 is a diagrammatic horizontal section of the same taken through line 8—8 of Fig. 7, and

Fig. 9 is a similar section of a modified 75 form of gravel and pump sump arrangement. Before taking up the detailed description

Before taking up the detailed description of the drawings, a brief exposition of the advantages and benefits to be derived from the hydraulic method evolved by the present invention over drifting and other methods formerly employed will be undertaken. The present method eliminates preliminary thawing of the material to be mined when operating on frozen ground; eliminates pick and shovel work, wheelbarrows and cars, and top sluicing. Mining operations may be carried on twenty-four hours per day if desired, and equally well during summer and winter, particularly in the Territory of Alaska, where it

has been necessary and advisable in many instances, for economical and other reasons, when employing old methods to close down during the winter months. The temperature in any part of the mine never falls below the 55 freezing point, a feature of considerable importance to the operators. Operations can be carried on at least three or four times more rapidly than by the old methods. The expenditure of effort on the part of operators

is materially reduced, inasmuch as cutting operations are performed by hydraulic giants, the mined material and water carried away by gravity, and the waste material mechanically hoisted to the surface.

Beginning now the more detailed description of the invention by reference to the accompanying drawings, the numeral 10 designates a section of ground to be mined, which is preferably, but not necessarily, of rectangular formation, as more clearly illustrated in Fig. 2. In practice such section is approximately eight hundred feet in length and five hundred feet in width, but it is to be understood that these dimensions may be varied and are only furnished here as an example.

In commencing mining operations on the section 10 a working shaft 11 is located substantially in the center of said section and is sunk into the bed rock designated by the numeral 12, which latter is cut into at or near the bottom of the shaft 11 to form a laterally extending passageway 13 enlarged at its outer end to form a pump chamber 14 and a longitudinally disposed water storage sump 15 extending therefrom.

Upwardly sloping working tunnels 16 are next driven into the bed rock at opposite sides of the shaft 11, said tunnels being longitudinally and medially disposed relative to the section 10, as more clearly illustrated in Figs. 2 and 3. The slope of the tunnels is such that the outer ends of the same are above the bed rock 12 and at or near the ends of section 10, as clearly illustrated in Fig. 1. In practical operation I have found that a slope of eight per cent provides an excellent sluicing grade plus a rise of seven or eight feet in the total length of each tunnel for drainage purposes.

Crosscuts 17 at the ends of the tunnels 16 are then driven into the material to be mined, such as gravel or pay dirt containing gold or other rare metals, such crosscuts being symmetrically arranged relative to the tunnels 16 and being made in order to initiate working faces 18 thereat.

Installed in the tunnels 16 and extending substantially the entire length thereof are sectional sluice boxes 19 provided at their adjacent or inner ends with swinging tail boxes 20, from which the sluicing water and waste material or tailings are selectively deposited in hoppers or settling boxes 21, which are disposed side by side at the tunnel mouths and below the plane thereof, said tunnel mouths being sufficiently enlarged to accommodate said hoppers, in the manner more clearly shown in Fig. 4. The hoppers 21 are preferably formed with inner and outer compartments, the former being designed to receive the waste material and gravel and to permit the sluicing water to overflow into the latter. The inner compartments of each set of hoppers 21 are provided with gates 22

and a common gravel discharge spout 23, while the outer compartments of such hoppers are provided with a common water discharge spout 24, from which the return sluicing water is discharged into a flume 25, which in turn empties into the sump 15. The contents of the inner compartments of each set of hoppers are adapted to be alternately hoisted to the surface by a hoisting bucket 26, actuated by any suitable means, not shown, each swinging tail box 20 permitting of the contents of one of its correlated hoppers being hoisted to the surface, while the other is being filled, as will be manifest and apparent by referring to Fig. 5, wherein a tail box 20 is illustrated in full lines in one position and in dotted lines in its other position.

Located in the pump chamber 14 is a pump 27, of any well known type, adapted to be driven by an electric motor 28, or in any other suitable manner, the suction side of said pump being provided with a suction pipe 29 having a terminal strainer 30 normally submersed in the water storage sump 15, while the discharge side of the pump is provided with a discharge pipe 31, which extends to the shaft 11 and branches thereat to form pipes 32, which extend through the tunnels 16 substantially the full length of the same. Connected to the outer end of each of the pipes 32 is a transversely disposed pipe or manifold 33 from which extend branches 34 having hydraulic giants or sluicing monitors 35 connected therewith.

When operating upon frozen ground the water in the storage sump 15 is preferably heated by a steam pipe 36, which receives steam from any suitable source of supply, not shown. In this connection it may be well to state, actual experience has shown that the temperature of the water for all practical purposes should be equal to or slightly above blood heat, such temperature being sufficient to effectively obtain simultaneous thawing and sluicing of frozen placers.

In carrying out the present method following initiation of the working faces 18 and installation of the hydraulic giants 35, the high pressure streams of water from such giants rapidly sluice or wash away the gravel or pay dirt from said faces, which gravel or pay dirt is conveyed by the sluicing water into the sluice boxes 19 and during passage therethrough, the gold in such gravel or dirt is extracted therefrom in a well known manner, so that only the waste material or tailings is deposited in one or the other of the hoppers associated with the particular sluice box 19. It is to be here noted that both the sluicing water and gravity are utilized in conveying the gravel or pay dirt through the sluice boxes. In the hoppers 21 the water is separated from the tailings and is conveyed by the flume 25 to the storage sump 15,

wherein it is heated by the steam pipe 36 and wherefrom it is returned under pressure to the working faces 18 by the pump 27, while the tailings from alternate hoppers are hoisted to the surface by the bucket 26, all as hereinbefore described.

It is of course apparent that the entire working faces 18 are gradually advanced due to the sluicing or washing action of the giants 35, which in the present instance are preferably arranged in echelon formation, so that such working faces are angularly and symmetrically cut relative to the longitudinal axis of the mine section 10, as more clearly illustrated in Fig. 2. As the working faces 18 advance the roof of the mine is quickly timbered in a well known manner, as by timbers or posts 37, to thereby properly protect the operators of the giants, which latter are moved up at intervals to the advancing faces 18, by adding pipe sections to the fluid pressure or water supply pipes 32, as will be manifest and evident.

Beginning with the initial working faces 18 and continuing during sluicing or cutting operations of the gravel or pay dirt great care is taken to provide a slight grade both longitudinally and laterally on the floor of the drift, as more clearly illustrated in Fig. 3, in order that the sluiced or cut material from the working faces will flow easily and rapidly to the tunnels 16 and into the sluice boxes 19 with the minimum impedance. To expedite and facilitate removal of the mined material from the floor of the drift during advancement of mining operations I have found it advisable and convenient to cut centrally aligned chutes 38 at intervals in the bed rock from the operating level to the tunnels 16 for the passage therethrough of said mined material to the sluice boxes 19. As each successive chute 38 is cut, as above described, that portion of the associated sluice box 19 extending beyond such chute may be dismantled or removed, there being no further use for the same in such location, see Fig. 6. In this connection, while I have shown the pipe 32, in Fig. 6, as extending the entire length of the tunnel and return-bent to extend to the advanced working face therein illustrated, it is to be understood that such pipe may be foreshortened if desired and passed up through any of the chutes 38, which feature will be obvious upon inspection.

When the working faces 18 are in proximity to the working shaft 11 and at a predetermined distance therefrom longitudinally and centrally disposed reversely sloping channels 39 are cut in the floor of the drift from said working faces to the nearest chutes 38, and sluice boxes 40 positioned therein to receive the sluiced material and convey the same to said chutes, this for the purpose of simplifying and expediting mining op-

erations at or near the working shaft 11, which are carried on up to the latter.

In Figs. 7 and 8, I have illustrated a slightly modified method and apparatus for separating the water from the tailings or gravel and for hoisting the latter to the surface, wherein the numeral 41 designates the working shaft, 42 the working tunnels, and 43 the sluice boxes located therein. The working shaft 41 is enlarged at the bottom to form a gravel or tailings storage sump 44 provided with a weir 45 over which the water flows to a pump sump 46. The discharge from the sluice boxes 43 falls directly into the storage sump 44 and is removed or hoisted to the surface by a clam shell bucket 47 of suitable capacity, operable by means not shown. The water in the pump sump 46 is heated by a steam pipe 48 and is returned under pressure from said sump to the working faces by an electrically driven pump 49.

In Fig. 9 a still further modified type of pump sump is illustrated, wherein the numeral 50 designates the working tunnels, 51 the gravel storage sump at the bottom of the working shaft, not shown, and 52 an overflow weir for the water to pass to a pump sump 53.

The present method and apparatus for underground hydraulic mining is particularly adaptable and especially suitable for working low grade frozen placers, inasmuch as the cost of installation and operation is comparatively low.

By locating the working shaft 11 in the center of the section 10 and providing two working tunnels for simultaneously conducting mining operations from both ends of said section, as herein shown and described, it will be obvious and apparent that such section is very rapidly and expeditiously mined. Also by starting at the outer ends of the section 10 and working inwardly, as herein set forth, the mined portions need never be entered again by the workmen, thus materially decreasing danger to the latter in the event of cave-ins occurring in such portions.

Manifestly, therefore, the present method and apparatus is simple and economical to install and operate; permits locating the pump, giants and water supply underground in a complete compact unit; permits the sluicing water to be used over and over again indefinitely, as loss of same through absorption or in the tailings is comparatively slight; permits the sluicing water being utilized for several purposes, first to simultaneously thaw and cut the material to be mined, and second to simultaneously convey and separate the gold or other rare metals from the mined material; and permits selecting or making any suitable sluicing grade.

While I have herein shown and described the invention with sufficient detail to enable those skilled in the art to which it pertains

to understand the same and the principles involved, it is to be understood that there is no intentional limitation herein to the specific method and precise details of construction shown and described, except as expressly defined by the appended claims, and that various modifications of the invention may be resorted to without departing from the spirit of the invention or the benefits derivable therefrom. It is also to be understood that certain features of the invention herein disclosed may be employed in and with other combinations than those shown and described.

What I claim as my invention and desire to secure by Letters Patent is:—

1. A method of underground hydraulic mining consisting in sinking a working shaft, driving a tunnel from said shaft adjacent the bottom thereof, driving a cross-cut at the end of said tunnel to establish a working face thereat, utilizing fluid pressure for cutting away the material to be mined, utilizing the fluid to convey the mined material to the working shaft and simultaneously therewith extracting the rare metals therefrom, separating the fluid from the waste material, elevating the latter to the surface, and returning the fluid under pressure to the working face.

2. A method of underground hydraulic mining consisting in sinking a work shaft into the bed rock, driving a tunnel from said shaft through the bed rock, driving a cross-cut adjacent the end of said tunnel and immediately above the bed rock to establish a working face thereat, utilizing fluid pressure for cutting away the material to be mined, utilizing the fluid to convey the mined material to the working shaft and simultaneously therewith extracting the rare metals therefrom, separating the fluid from the waste material, elevating the latter to the surface, and returning the fluid under pressure to the working face.

3. A method of underground hydraulic mining consisting in sinking a working shaft, driving an upwardly sloping tunnel from said shaft, driving a cross-cut adjacent the end of said tunnel to establish a working face thereat, utilizing fluid pressure for cutting away the material to be mined, utilizing the fluid to convey the mined material to the working shaft and simultaneously therewith separating the rare metals therefrom, separating the fluid from the waste material, elevating the latter to the surface, and returning the fluid under pressure to the working face.

4. A method of underground hydraulic mining consisting in sinking a working shaft into the bed rock, driving an upwardly sloping tunnel through the bed rock to the material to be mined, initiating a working face in said material, utilizing fluid pressure for

cutting away the latter, utilizing the fluid to convey the mined material to the working shaft and to extract the rare metals therefrom, separating the fluid from the waste material, elevating the latter to the surface, and returning the fluid under pressure to the working face.

5. In underground hydraulic mining, a method consisting in sinking a working shaft, driving a tunnel from said shaft with a sluicing grade, driving a cross-cut at the end of said tunnel to establish a working face thereat, and mining towards said shaft.

6. In underground hydraulic mining, a method consisting in sinking a working shaft into bed rock, and driving an upwardly sloping tunnel from said shaft through said bed rock to the material to be mined, whereby said material is mined in the direction of the shaft and said tunnel is utilized for conveying the mined material from the point of excavation to the bottom of said working shaft.

7. In underground hydraulic mining, a method consisting in sinking a working shaft in bed rock, driving a gravity tunnel from said shaft through said bed rock to the material to be mined, utilizing fluid under pressure for cutting away such material in the direction of the shaft, and utilizing the fluid and tunnel grade for conveying the mined material from the point of excavation to the bottom of said working shaft.

8. In underground hydraulic mining, a method consisting in sinking a working shaft, driving a gravity tunnel from said shaft to the material to be mined, initiating a working face thereat mining said material in the direction of said shaft, and cutting chutes at intervals from the operating level to the gravity tunnel during advancement of mining operations.

9. In underground hydraulic mining, a method consisting in sinking a working shaft into the bed rock, driving a tunnel with a sluicing grade through the bed rock from said shaft to the material to be mined, initiating a working face thereat mining said material in the direction of said shaft, and cutting chutes at intervals in the bed rock from the operating level to said tunnel during advancement of mining operations.

10. In underground hydraulic mining, a method consisting in sinking a working shaft, driving a gravity working tunnel from said shaft to the material to be mined, initiating a working face thereat mining said material in the direction of said shaft, and establishing a slight grade longitudinally and laterally on the floor of the drift during mining operations for conveying the mined material to said gravity tunnel.

11. In underground hydraulic mining, a method consisting in sinking a working shaft, driving a gravity working tunnel from said

shaft to the material to be mined, initiating a working face thereat, cutting chutes at intervals from the operating level to the gravity tunnel during advancement of mining operations, and finally at a predetermined distance from said shaft establishing a reversely disposed sluicing grade from the operating level to the nearest chute, whereby the mined material is sluiced from the working face to the gravity tunnel.

10 12. In an underground hydraulic mine, the combination of a working shaft, a working face initiated at a distance therefrom and communicating therewith, fluid storage means in said mine, and sluicing means for cutting said work face in the direction of said shaft adapted to receive fluid from said storage means.

15 13. In an underground hydraulic mine, the combination of a working shaft, a working tunnel leading from said shaft, a working face initiated at the outer end of said tunnel and communicating therewith, fluid storage means in said mine, sluicing means for cutting said working face in the direction of said shaft adapted to receive fluid from said storage means, and means for returning the fluid to said storage means following sluicing operations.

20 14. In an underground hydraulic mine, the combination of a working shaft, a working tunnel extending therefrom, a working face having communication with said tunnel, fluid storage means in said mine, sluicing means adapted to receive fluid from said storage means for cutting away the material to be mined from said working face, means for conveying the mined material and fluid from the working face to the working shaft and simultaneously therewith extracting the rare metals from said material, means for separating the fluid from the waste material and returning such fluid to said storage means, and means for elevating the waste material to the surface.

25 15. In an underground hydraulic mine, the combination of a working shaft, a working face initiated at a distance therefrom and communicating therewith, fluid storage means in said mine, means for heating the fluid in said storage means, sluicing means adapted to receive heated fluid from said storage means for thawing and cutting away said working face in the direction of said shaft, and means for returning the fluid to said storage means.

In testimony whereof I affix my signature.
SYLVESTER HOWELL.
